Fig. 1.

Fig. 5.

Fig. 2.

This technical drawing illustrates a floor joist assembly. The main structure is a rectangular joist with a top flange and a bottom flange. The top flange features a series of circular holes. A hanger system is attached to the top flange, consisting of a horizontal strap with two vertical legs. The top leg is secured to the top flange, and the bottom leg is secured to the bottom flange. The hanger is labeled with the number 28. A vertical support, also labeled 28, is attached to the side of the joist. A horizontal dimension line with an arrow indicates a width of 4 inches. The drawing is signed 'Fig. 3.' in the bottom left corner.

FLUID DISTRIBUTION AND DISTRIBUTOR

Robert M. Shirk, Wilmington, Del., assignor to Houdry Process Corporation, Wilmington, Del., a corporation of Delaware

Application September 23, 1957, Serial No. 685,673

5 Claims. (Cl. 34—57)

This invention is concerned with the distribution of large volumes of compressible fluids, such as gases and vapors, in confined regions containing particulate solids. More particularly it is concerned with the provision of means and techniques whereby the high velocities of the fluids thus introduced are reduced to below the velocity at which disturbance of the solids in a bed or layer thereof would be effected.

The introduction of compressible fluids into enclosed vessels and the like has encountered many problems, and attempts at their solution have been made more or less successfully with a legion of introduction devices including nozzles, lances, open-ended pipes, channels, manifolds, and so on. In the realm of hydrocarbon processing operations, particularly, large volumes of gases and vapors are processed under a wide range of conditions in variously formed vessels to achieve results such as the preparation of high quality gasoline and/or specific chemicals, either *per se* or as separable components in mixed product. The effective use of catalysts for promoting various hydrocarbon reactions is well established, and a high percentage of hydrocarbon processing is effected in the presence of such catalysts which may have physical form generally ranging from very minute particles to coarse granules or pellets which have dimensions generally in the range of about $\frac{1}{32}$ to $\frac{1}{2}$ inch in diameter. Some of the hydrocarbon reactions are effected in the presence of mixed sized ranges of generally minute particles maintained at a pseudo liquid condition identified in the art as "fluid" operations. The present invention is directed more particularly to catalytic operations employing the generally larger sized particles such as those in the range of $\frac{1}{32}$ to $\frac{1}{2}$ inch in diameter which are maintained in a relatively compact bed of fixed position within a reaction vessel and wherein such fixed position is to be maintained without substantially disrupting or dislodging the particles of solid throughout the course of the reaction or reactions taking place in the presence thereof.

While it should be understood that no limitation is to be placed on the invention because of the description in connection with a specific type operation, the description will be in terms of a known catalytic operation in which gasolines and naphthas are reformed to improve their motor fuel value, particularly the octane ratings, in the presence of commercially available catalyst comprising a minor amount of platinum supported on alumina and having dimensions in the order of about $\frac{1}{16}$ to $\frac{1}{4}$ inch. It has been found that under the proper selected operating conditions, such catalyst is quite effective in promoting the desired reaction, and that large volumes of the vaporized hydrocarbons can be processed over relatively small amounts of catalyst. In the interest of economies, the quantity of this expensive catalyst necessary to effect the desired reaction is held to a minimum and the reaction vessel utilized for these reactions is likewise constructed with as little excess space and equipment as is reasonably feasible.

2

The problem arising in connection with an operation of this sort is that very large volumes of vapors are desirably introduced into a relatively small space under conditions resulting in turbulent fluid flow. Uncontrolled or not suitably positioned introduction of the large fluid volumes may result in velocities at one or more regions within the introduction area such that at times violent whirling and lifting of the particles in the uppermost portion of the bed is encountered, or in other instances the particles comprising the surface of the reaction bed may be distributed and dislodged from their proper position to lesser extent but still to a degree not only interfering with the proper conduct of the reaction, but also having detrimental effect on the catalyst and equipment through abrasion, attrition and the like. In order to overcome this problem, the available forms of introduction were considered and found unsuitable for one or more reasons.

While certain estimations and calculations of expected gas velocities are possible in connection with flow through pipes, orifices and the like on the basis of known fundamentals of fluid dynamics, theoretical analysis of velocity distribution as a result of introduction of turbulent streams of gas from a conduit into a confined space containing gas at rest or in motion presents considerable difficulty. Calculations on a strictly mathematical basis have proved unreliable because of the unavailability of fundamental data on many of the encountered situations and because of accompanying changes in the characteristics of the fluid as a result of variations and changes during flow. Changes in the temperature, pressure, density and viscosity, besides those due to any chemical transformations that may have taken place in transit have marked effect on the velocity. For these reasons, despite continuing investigation and development of fundamental data to serve as a basis of determining expected behaviour of the flowing gas under numerous encountered conditions, high safety factors are still being introduced by way of costly overdesign of equipment for fluid distribution; or, at times, hit or miss predictions based on empirical experience in other situations thought to be parallel have resulted in the construction of inadequately designed systems. While the investigation of new situations in prototype models and pilot plants would reduce the elements of chance design, such investigation is quite costly and cannot be afforded in all instances from the standpoint of time and expense involved.

As a result of extensive independent studies and observations of fluid behavior to supplement the fundamental information available in prior literature to the extent found reliable, there is provided by the present invention a novel method for handling large volumes of gases and vapors introduced into a treating vessel containing a fixed bed of granular solids enabling the use of adequate equipment at economic construction costs.

In accordance with this invention, introduction of a large volume of compressible fluid within a confined region above the surface of a fixed bed of particulate solids at an overall velocity at the surface of said solids below the disturbance velocity is obtained by reducing the velocity of the introduced fluid in several manners. The fluid entering through the vessel inlet is first caused to flow through a distributing manifold having multiple outlet ports discharging generally across the upper section of said manifold. The size and number of such ports is designed to provide a total effective discharge area greater than the area of the inlet to the vessel. The total distance of any one discharge port from the nearest reflecting surface is at least seven times the diameter of the port, to overcome the effect of sustained axial velocity as hereinafter explained. In this manner the maximum fluid velocity is so reduced in a magnitude that the portion of

the fluid flowing at or into the surface of the bed is maintained below a critical value represented by the formula:

$$V_d = 7.82 \sqrt{\frac{D_c \rho_c}{\rho_f}}$$

Where:

V_d = velocity in feet per second - disturbance velocity.

D_c = diameter of particles in feet.

ρ_c = particle density in pounds per cubic feet.

ρ_f = gas density in pounds per cubic foot at flowing T. and P.

The reduction of fluid velocity as a result of increased flow area is well understood in that at any given volumetric flow rate the average linear velocity of the fluid flowing through a confined path is inversely proportional to the area of the path. In the description, however, reference is made to the "effective discharge area." This designation takes into consideration the coefficient of contraction of the fluid stream passing through an orifice to provide a "vena contracta" beyond the orifice. As a result of such stream contraction, the average velocity, and more importantly the velocity at the axis of the stream, is greater than that calculated on the basis of considering the actual diameter of the port. To overcome the effect of such velocity increase, accordingly, the size and number of the ports in the distributing manifold is designed to provide a total efflux area of not less than 1.7 times that of the vessel inlet, and preferably, in the case of inlet gas velocities approaching or exceeding 100 feet per second at the inlet, the total discharge area of the ports in the manifold should be 2 to 3 times that of the inlet.

Reference has been made above to the axial velocity of the fluid stream discharged from a port or orifice as distinguished from the average velocity of such stream. A stream of gas discharged into a large area through confining conduit or port forms a jet having free turbulence characterized by eddies which move at different velocities. The jet can be considered as subdivided into three regions according to the axial distance from the discharge port, which are termed: the potential cone region, the transition region and the developed flow region. The potential cone region is the cone shaped zone having an apex above the discharge port, in which region the fluid velocity remains equal to the original velocity at the discharge port. The surface of this potential cone represents the limit to which mixing has penetrated into the original fluid stream and the tip of the cone represents the point at which turbulent mixing has reached the axis of the fluid jet. The apex of this cone has been found experimentally to lie at a distance from the discharge port of approximately 4 times the diameter of the port. In the mixing region surrounding the cone of undiminished fluid velocity, there is a loss in the linear velocity component with increase of distance from the port.

In the developed flow region, some distance beyond the apex of the cone turbulent mixing has reached an asymptotic state. Here radial velocity profiles and the velocity distribution at the axis can be reliably ascertained by relatively simple theoretical treatment. In the transition region between the apex of the cone and the beginning of the developed flow region the velocity distribution is changing from the characteristics of the potential cone region to those prevailing in the developed flow region. No theoretical treatment applicable to this transition region has been fully developed.

This transition region has been found to extend for a distance beyond the cone region of 7 to 8 diameters from the discharge port. To arrive at a reasonably reliable basis for estimation of the rate of velocity decline of the fluid stream, the discharge ports in the manifold are located at a distance from the reflecting (or deflecting) surface nearest thereto such that in flow from such surface there obtains the characteristic velocity decline of fluid flow in the developed flow region. The rate of such

velocity decline can be readily calculated so that the proper distance can be provided from the reflecting surface to the surface of the particle bed to assure that the maximum critical velocity V_d is not exceeded. This rate of decay in the region of developed flow has been found from plotting of experimental data to conform to the equation:

$$\frac{U_a}{\bar{U}_o} = \frac{6.7}{x/D_o}$$

in which:

U_a = fluid velocity at the axis of the stream at any point on said axis,

15 $\bar{U}_o$ is the average discharge velocity of the stream at the port,

x is the axial distance from the discharge port to such point, and

D_o is the diameter of the port.

20 Applying the above formula and as confirmed by experimental results, the rate of approximate decline of maximum velocity (at the axis of the stream) will be seen from the following tabulation:

x/D_o	$U_a/\bar{U}_o$
8	0.84
12	0.59
16	0.42
20	0.33
24	0.28

30 Thus, it is seen that in flowing from the discharge port toward a reflecting surface the gas stream has about reached or has entered into the fully developed flow region so that its maximum velocity has been reduced by at least 10 to 15%. In flowing from such surface to the bed the fluid stream in addition to some velocity loss depending on the angle of impact, loses velocity at the characteristic rate for the developed flow region in following an unobstructed path permitting association and mixing with vapors in the surrounding atmosphere at all portions of the periphery of the stream.

35 Fuller understanding of the invention may be had by reference to the following description and claims taken in connection with the accompanying drawing forming a part of this application in which:

40 Fig. 1 is a cross sectional view of a spherical reaction vessel incorporating a distribution manifold of the type contemplated by the invention;

45 Fig. 2 is a plan view of the distribution manifold taken at line 2—2 in Fig. 1;

50 Fig. 3 is a plan view of an enlarged segment of the distributing member shown in Fig. 2;

55 Fig. 4 is a cross sectional elevation taken at line 4—4 on Fig. 3;

Fig. 5 is a plan view of a modified distributing manifold embodiment; and

Fig. 6 is a cross sectional elevation taken at line 6—6 on Fig. 5.

60 Referring to Fig. 1, there is shown a spherical reactor vessel 11 having an internal diameter of approximately 10½ feet. Horizontally positioned within and spaced apart from the bottom area of vessel 11 is a grating support 12 on which is positioned a 4 inch layer of ¾ inch diameter alumina spheres 13 which in turn supports a 4 inch layer of ½ inch diameter alumina spheres 14 which in turn supports a layer of platinum on alumina reforming catalyst particles forming a fixed bed approximately 5 feet 3 inches in depth indicated as 15. Covering the catalyst layer and supported thereby is an additional 4 inch layer 16 of ½ inch diameter alumina spheres giving a bed surface of about 56.7 square feet and leaving approximately 237 cubic feet of space, above the bed surface, as the confined region into which the charge gas is introduced.

65 70 75 It is to be understood that the description is of an em-

bodiment of a particular operation and is not indicated to be limiting in substances, quantities or measurements. For instance, the size and distribution of the alumina spheres may vary as may the size of the catalyst bed as well as the type of catalyst. As will be noted herein-after, the size and shape of the reaction vessel and the interior therefore may likewise be varied to suit conditions and design classification.

Horizontally positioned above and spaced apart from the upper layer of alumina spheres 16 is gas distributing manifold 17 supported in an axial position by feed member 18 and strap 19. Strap 19 in turn is fastened to man-way 21 which is normally closed by seal plate 22. Man-way 21 may be used for access to the interior of vessel 11 when necessary.

In the lower region of vessel 11 a suitable solids discharge pipe 23 is in direct communication with the portion of the reactor vessel above supporting grating 12. Pipe member 23 is sealed by means not shown to prevent passage of solids or gases during operation. Around the centrally positioned vertically extending pipe member 23 is a gas removal conduit 24 in open communication at its upper end with the plenum 26 existing between the lower part of vessel 11 and supporting grating 12. The gas discharge conduit 24 discharges into suitable transfer members, not shown, and serves as the means through which reaction products are recovered. Grating 12 is supported peripherally by the walls of vessel 11 and internally by support members 27.

In the normal operation of a reactor, as herein described, for the reforming of a gasoline boiling range charge stock, it has been found, for the desired quantity of charge introduced through a nozzle of approximately 18" I.D., the gas discharges from the feed member or nozzle 18 at approximately 100 ft./sec. and has a velocity at the surface of the bed in the range of at least 65-70 ft./sec. At such high gas velocity there is considerable and violent disturbance and disruption of the solids in the bed, with attendant breakage of the catalyst, erosion of equipment, and a rapid increase in the pressure drop through the catalyst bed because of an accumulation of the broken catalyst particles in the bed. It was found further that when a trough-like deflection member was positioned between the nozzle and the bed surface to prevent direct access of the incoming gas stream to the surface of the bed the gas velocities at the surface of the bed were still in the order of 45-50 ft./sec. at portions of the bed surface. At these velocities and in accordance with the previously described formula, an appreciable amount of churning and moving of solids particles in the upper portion of the bed resulted in appreciable breakage and attrition with unsatisfactory gas flows through the bed of catalyst. In order to obtain a practical operating gas velocity, gas distribution member 17, as shown more fully in Figs. 2, 3 and 4, was installed and serviced by nozzle 18.

With the reactor system described in connection with Fig. 1, the highest permissible gas velocity as determined through application of the above-described formula at the surface of the bed could not be greater than 28 ft./sec. With the gas distribution through gas distribution member 17, constructed as hereinafter described, the gas velocities at the bed surface were uniformly in the range of about 18-23 ft./sec. and thus well within the safe operating limit.

Referring now particularly to Fig. 2, gas distribution member 17 is shown as a hexagonal ring type member served by nozzle 18 and discharging gas therefrom through one inch ports positioned in the upper 120° of the five segments exclusive of the segment in which gas nozzle 18 is attached. Avoiding discharge from the segment in which the main gas stream is introduced provides for better distribution of the gas in the manifold and insures more nearly equal gas flow to the ports in the other segments. The general distribution and location of the

discharge ports 28 are shown in more detail in Fig. 3. In accordance with the previously described system, the size of the discharge ports is such that the distance therefrom to the nearest reflecting surface, e.g., the upper wall of vessel 11, is greater than seven times the diameter of any individual port; that is, for these 1 inch ports no one of these is at a distance of less than 7+ inches from the nearest reflecting surface.

In the particular system described, direct introduction of the required gas volume resulted in a gas velocity at the discharge end of nozzle 18 in the order of 100 feet per second through an effective discharge opening of approximately 254.5 square inches. The jet effect of the incoming gas continued with only minor exterior decay (to about 70 feet per second average velocity) at the surface of the bed—a travel distance of about 2½ feet and substantially less than seven or more times the diameter of nozzle 18.

The introduction of a baffle between the opening of nozzle 18 and the bed surface in such manner as to redirect the incoming jet away from direct contact with the bed surface without changing the effective discharge rate of the nozzle effected some reduction in the velocity of the gas reaching the bed surface; however, this velocity, averaging about 50 feet per second, was still far too high for successful operation.

With the attachment of manifold 17 to nozzle 18 there was still no material effect on the velocity of the gas emerging from nozzle 18 into manifold 17. Now, however, this gas introduced into manifold 17 is redirected and discharged through 585 ports or nozzle openings 28 having a total effective opening area of approximately 459 square inches, almost double that of nozzle 18. In addition, each of the openings 28 is so positioned as to discharge gas flowing therethrough in a direction away from the surface of the bed. In further consideration it is seen that the jet effect of the individual gas stream is successfully dissipated in that the distance of travel to the wall of every single gas jet passing through openings 28 is generally greater than seven times the effective opening (one inch diameter) of each of openings 28. As a result of this method of gas introduction, the velocity of the gas at the bed surface was in the order of 20 feet per second and thus well below the allowable upper limit of about 28 feet per second for the particular system herein described.

The positioning of the discharge ports such that the gas passing therethrough is directed toward a wall surface or surface other than the surface of the bed of particles thus gives an added measure of protection against unduly high local velocities at the bed surface. As previously stated the positioning is such as to permit the full decay of the individual jet effect at or before reaching a wall surface, and even with a malfunctioning jet stream not fully dissipated before reaching the wall such a jet still has the return distance either along an expanding path due to wall curvature or through space to permit loss of any jet effect with concomitant velocity decrease to an acceptable average value prior to reaching the bed surface.

The embodiment set forth in Figs. 1 through 5 contemplates a specific reaction system. As previously indicated, reasonable deviations are within the scope of this invention. For example, a cylindrical vessel horizontally positioned is suitably used in connection with a gas distributor nozzle system shown in Figs. 5 and 6 wherein a centrally located inlet line 31 feeds into spider member 32 which in turn discharges relatively uniformly into gas distribution member 33. Member 33 has gas distribution ports positioned in the upper half thereof for discharge into the upper region of the reactor vessel in accordance with the requirements of size and number of openings, travel distance and the like to give velocity in accordance with the foregoing description. Other nozzle forms and gas distribution member forms, such as

square, circular or other, are likewise within the scope of this invention.

Obviously many modifications and variations of the present invention as hereinbefore set forth may be made without departing from the spirit and scope thereof and therefore only such limitations should be imposed as are indicated in the appended claims.

I claim:

1. In a reactor vessel containing a fixed bed of granular material extending throughout an intermediate level therein and being spaced from its upper end so as to provide therewith a plenum having the surface of said bed as its lowermost boundary, a gas feed nozzle communicating with said plenum, and gas withdrawal means at the bottom of said bed, the configuration and size of said plenum and the location and size of said gas feed nozzle being such that for design input of gaseous material through said nozzle the velocity of gas flowing directly therefrom to said surface of the bed would exceed the bed-disturbing velocity (V_d), as determined by the formula:

$$V_d = 7.82 \sqrt{\frac{D_c \rho_e}{\rho_f}}$$

wherein D_c is the average diameter of solid particles in said bed, ρ_e the particle density and ρ_f is the density of the fluid the combination therewith of: a gas distributor comprising a horizontal manifold conduit supported within said plenum and above the surface of said bed, said manifold conduit having a plurality of upwardly directed ports whose total discharge area exceeds the discharge area of said gas feed nozzle in the ratio of at least 1.7

5 to 1 and each of said ports being spaced from the plenum-bounding portion of the vessel wall a distance, measured along the port discharge axis, of at least 7 times the diameter of the port; the size, number and arrangement of said ports being such as to substantially reduce the velocity of the incoming gas stream whereby the velocity of the gas at all points on the surface of said bed will be less than said bed-disturbing velocity.

10 2. Apparatus as in claim 1 in which the total discharge area of said ports exceeds the discharge area of said gas feed nozzle in the ratio of between 1.7:1 and 3:1.

3. Apparatus as in claim 1 in which said distributor has a region of free flow area greater than the discharge area of said gas fed nozzle.

15 4. Apparatus as in claim 1 in which said distributor comprises a circumferentially complete tubular member having an inlet connector communicating with said feed nozzle, and being provided along its entire upper curve surface with uniformly spaced ports, the axis of discharge of said ports being directed toward the upper end walls of said vessel.

20 5. Apparatus as in claim 4 in which the configuration of the continuous tubular member conforms in general to the surface outline of the bed, so that all portions of 25 the tubular member may service substantially equal portions of the bed.
